UNITED STATES PATENT OFFICE.

ISAAC M. HACKNEY, OF WICHITA, KANSAS.

ACETYLENE GENERATOR.

Application filed August 6, 1920. Serial No. 401,707.

To all whom it may concern:

Be it known that I, ISAAC M. HACKNEY, a citizen of the United States, residing at Wichita, in the county of Sedgwick and State of Kansas, have invented a certain new and useful Improvement in Acetylene Generators, of which the following is a specification.

My invention relates to improvements in acetylene generators. It relates particularly to novel means for controlling the feeding of carbide into the water of a generating chamber.

The object of my invention is to provide a novel apparatus of the kind described, which is simple in construction, cheap to make, reliable in operation, durable and not liable to get out of order, which will retain the gas pressure in the generating chamber at substantially a pre-determined amount, which can readily be adjusted to operate under different pressures, without stopping the operation of the apparatus, and which is efficient in operation.

My invention provides further novel valve mechanism for controlling the passage of gas from the generating chamber to the dry gas container.

My invention provides still further novel means for regulating the feed of carbide into the water.

My invention provides still further novel means for controlling the carbide feeding mechanism.

The novel features of my invention are hereinafter fully described and claimed.

In the accompanying drawings, which illustrate the preferred embodiment of my invention,

Fig. 1 is a view, partly in elevation, partly in vertical section and partly broken away, of my improved acetylene generator.

Fig. 2 is a top view of the same.

Fig. 3 is a horizontal section on the line 3—3 of Fig. 1.

Fig. 4 is an enlarged cross section on the line 4—4 of Fig. 1.

Fig. 5 is an enlarged vertical sectional view of the carbide feeding mechanism and parts connected therewith.

Fig. 6 is an enlarged cross section on the line 6—6 of Fig. 1.

Similar reference characters designate similar parts in the different views.

1 designates the generating chamber, which may be of any desired form, and

which is adapted to contain water 2, into which the carbide 3 is fed for the production of the acetylene gas. The carbide 3 is held in the hopper 4 having a converging bottom provided at its lower end with a discharge opening 5, and supported at its upper end by an internal annular flange 6 provided on the under side of the generating chamber cover 7, which has a vertical screw-threaded opening through which carbide is fed into the hopper, the opening being normally closed by means of a screw plug 8. The cover 7 is preferably removable and is clamped to the body by means of bolts 9.

The side wall of the chamber 1 is provided with a water inlet 10 normally closed by a removable plug 11 and through which the water is poured into the generating chamber, 1.

For dumping the carbide 3 into the water 2, I provide a valve, preferably comprising a scoop-shaped bucket 12, which is tiltably mounted on a horizontal pin 13, which extends through opposite walls of the bucket 12, and which is mounted in the lower end of an inclined plate 14, the upper end of which is attached to the hopper 4. The bottom of the bucket 12 is inclined as shown in solid lines in Fig. 1, and in dotted lines in Fig. 5, when in the discharge position of the bucket. The bottom of the bucket is disposed horizontally, so as not to spill out any carbide, when the bucket is moved from the discharge position to the position shown in solid lines in Fig. 5.

Extending transversely between the side walls of the bucket 12 and below the opening 5 and closely adjacent to the plate 14, is a false bottom 15 arranged to receive and retain thereon the carbide when the bucket 12 is in the discharge position and which is inclined so as to discharge carbide on the bottom of the bucket when the latter is swung from the discharge position to the position shown in solid lines in Fig. 5.

There is a space 16 between the discharge end of the false bottom 15 and the bottom of the bucket 12 through which the carbide passes. In order to prevent the carbide from clogging in this narrow space, I provide means for poking the carbide through said space when the bucket 12 is swinging to the discharge position. This poking means comprises preferably a resilient member 17 having one end rigidly secured to the hopper

4 and having its lower end adapted to enter the space 16, so as to push carbide there-through.

When the bucket 12 is in the discharge position, carbide will pass from the hopper 4 onto the horizontally disposed false bottom 15 and will be retained thereon. When the bucket 12 is swung from the discharge position, to the position shown in solid lines 10 in Fig. 5, the carbide will slide from the false bottom 15 onto the bottom of the bucket, and when the bucket has again been swung to the discharge position, the carbide which is on the bottom of the bucket will 15 be dumped into the water 2, thus generating gas and producing a pressure in the generating chamber 1.

The amount of carbide discharged at each time into the water will depend upon the 20 size of the space 16.

For tilting the carbide holder 12 to and from the discharge position by means controlled by gas pressure, I provide suitable means which may consist in the following 25 described parts.

Mounted on the cover 7 is a closed receptacle 18 having a removable cover 19, which may be fastened to the body of the receptacle by bolts 20, and which is provided with 30 a screw-threaded hole in which is normally fitted a screw plug 21. By removing the screw plug, water or other sealing liquids, may be poured into the receptacle 18, until it reaches the level of a screw-threaded hole 35 in the side of the receptacle, which hole is normally closed by means of a screw plug 22, Fig. 1.

The receptacle 18 near its lower end is 40 provided with a drainage outlet normally closed by a removable plug 23.

The receptacle 18 has in its bottom a vertical central hole through which extends a gas conductor comprising a vertical pipe 24, having an annular flange 25, which bears 45 against the upper side of the bottom of the receptacle 18, and which has an externally screw-threaded lower end fitted in a threaded opening in the cover 7, and on which is mounted a removable lock nut 26, which 50 bears against the under side of the cover 7, thus securely clamping the receptacle 18 to the cover 7.

The lower end of the conductor 24 extends into and is spaced apart from an ordinary coupling 27 fitted in the upper end 55 of a vertical pipe 28, which extends through and is rigidly secured to the bottom of the hopper 4. The lower end of the conductor 24 has preferably fitted in it a ring 29, Fig. 1, which makes a restricted passage for gas.

Mounted in the sealing liquid, 30, in the receptacle 18, is a gas bell 31, which encircles the conductor 24, and into which the upper end of said conductor discharges gas 60 which is adapted to lift the gas bell 31, until

the latter has its upward motion limited by means of a nut 32, which is fastened to the lower screw-threaded end of a vertical rod 33, the upper end of which is screw-threaded and extends through the top of the gas bell 70 31, and through the lower end of a yoke 34, which is clamped to the gas bell 31, by a nut 35, mounted on the upper end of the rod 33, and by a nut 36, mounted on the rod 33 and bearing against the under side 75 of the top of the gas bell 31.

The upper end of the yoke 34 is slidably mounted upon the vertical reciprocative operating rod 37, having at its lower end under the top of the yoke 34 a head 38 by means 80 of which the yoke 34 and with it the gas bell 31 and rod 33 may be lifted manually.

The rod 37 extends through a stuffing box 39 provided in the center of the cover 19. In the automatic operation of the apparatus, the rod 37 merely serves as a guide for the gas bell 31, through the intermediacy of the yoke 34. At such time, the rod 37 is held in a position in which the nut 35 will not strike the head 38 by a right-angled rod 40, 90 one arm of which is horizontally pivoted to the upper end of the rod 37, and the other arm of which is adapted to be swung to a vertical position so as to rest upon the cover 19, as shown in Fig. 1. The rod 37 adjacent to its upper end is provided with a transverse pin 41, which forms a hand hold by which the operator may vertically reciprocate the rod 37, for the purpose of vertically moving the gas bell 31, to effect a 100 preliminary generation of gas in the generating chamber, when the machine is first started into operation.

The screw-threaded lower end of the rod 33 extends through one end of a right-angled rod 42, one arm of which is clamped to the rod 38 by means of two nuts 43 and 44 mounted on the rod 33, and respectively secured in position by lock nuts 45 and 46, Fig. 5. The other arm of the rod 42 is 110 loosely fitted in a slot 47, in a horizontal part of a right-angled plate 48, which is secured to one side of the bucket 12. Two pins 49 and 50 are mounted in the vertical arm of the rod 42 respectively above and 115 below the plate 48.

The rod 33 extends through the conductor 24, coupling 27, and pipe 28. When the gas bell 31 is lifted by gas pressure, the rod 33 is lifted and with it the rod 42, thereby lifting the holder 12 from the discharge position to the position shown in solid lines in Fig. 5. When the bell 31 falls, the holder 12 is swung to the discharge position shown in solid lines in Fig. 1, and in dotted lines 120 in Fig. 5, by means of the rod 33, rod 42, and bracket 48.

The cover 19 is provided with a threaded outlet 51, Fig. 1, in which is fitted one end 125 of a line of piping 52 which discharges into

a container 53 adapted to hold water through which the gas passes to the upper part of the gas container, the latter having above the level of the water in the container 53 a gas outlet in which is fitted a discharge pipe 54, which may be provided with a shut off valve 55 and to which a torch or other device, not shown, may be applied for utilizing the gas.

10 The line of piping 52 adjacent to the container 53 is provided with a check valve 56 which opens toward the container 53. The lower end of the container is provided with a removable cap 57 having a drainage opening in which is normally fitted a removable plug 58. The side of the container is also provided with a hole in which is normally fitted a removable plug 59. In placing water in the container 53, the plug 59 is 15 removed and water is poured into the container until the water runs out of the hole from which the plug 59 was removed, upon which the plug 59 is replaced.

15 In the line of piping 52 between the check valve 56 and the receptacle 18 may be provided a shut off valve 60, which when closed, closes the flow of gas through the piping 52 and renders the apparatus inactive. Normally the valve 60 is open.

20 Connecting the generating chamber and the container 53 is another gas conducting means comprising, preferably, piping 61 which discharges at its lower end into the gas container 53 below the level of the water 25 therein and which is adjacent to the container 53 is provided with a check valve 62 which opens toward the container 53. The piping 61 is provided with a T joint 63 having attached to it an elbow 64 in which is 30 fitted a removable plug 65. When the plug 65 is removed, water may be poured into the elbow 64. The water will pass through the piping 61 into the container 53. When the water emerges from the hole which normally contains the plug 59, the plug is 35 replaced.

35 Forming part of the gas conducting means now being described, is a valve casting comprising a lower shell 66 mounted in the upper end of the T joint 63 and having a vertical tubular seat 67, which has slidably fitted on it and adapted to close it a valve 68 having a cup shaped lower end fitted to the tubular seat portion and resting upon the upper end of the latter so as to close said end when the pressure in the generating chamber 1 is below a pre-determined amount. The inner wall of the cup shaped lower end of the valve 68 has vertical grooves 69, Fig. 6, through which gas may pass when the valve is in the open position.

40 The valve 68 has its upper end attached to the center of a horizontal diaphragm 70, which at its edges is clamped between the

lower shell 66 and an upper shell 71, the lower end of which has threaded connection with the upper end of the lower shell 66. Suitable means is provided for holding the valve 68 closed until a predetermined pressure on the underside of the diaphragm 70 lifts the valve to the open position. Such holding means may be adjustable, so that the pre-determined pressure required to open the valve may be changed as desired. For this purpose may be provided a vertical coil spring 72, the lower end of which bears against the upper side of the central portion of the diaphragm 70, and the upper end of which supports a plate 73 against the upper side of which bears the lower end of a vertical adjustable screw 74, which is fitted in a threaded hole in the upper end of the shell 71. The latter may have removably fitted on it a screw cap 75 which normally covers the head of the projecting screw 74. The screw 74 is accessible, on removing the cap 75, from the exterior of the apparatus, so that the tension of the spring 72 may be changed, without shutting down the apparatus, so as to change the pre-determined pressure at which the valve 68 will open.

45 Attached to one side of the lower shell 66 is a T joint 76 to which is connected an ordinary pressure gage 77. A pipe 78 connects the T joint 76 with the generating chamber 1.

50 In the operation of the invention, to obtain a preliminary working pressure in the container 53 the valve 60 is opened, and the valve 55 is closed. The operator attaches to the pipe 54 the torch provided with the burner tip that he desires to use for the particular purpose in view.

55 A supply of carbide is placed in the hopper 4, and the nut 32 is adjusted so as to limit the upward movement of the bell 31 to a point at which a small amount of carbide, preferably from one fourth to one half an ounce, will be dumped into the bucket 12 from the plate 15. By adjustment such that small charges are dumped, the oscillations of the bell 31 and bucket 12 will be more frequent, and the pressure retained more uniform, than with an adjustment for larger charges.

60 Water is placed in the container 53, to prevent backfiring. The generating chamber 1 is filled with water to the level of the inlet 10, and sufficient water should be placed in the chamber 18 to insure the bell 31 making a full upward stroke. If a larger amount of water is placed in the chamber 18, just a little more pressure is required to lift the water to permit the gas to blow through it.

65 The angle rod 40 is turned at right angles to the position shown in Fig. 1, and the rod 37 is drawn upwardly, thereby lifting the

yoke 34, and with it the rod 33 and bell 31 until the nut 32 strikes the lower end of the pipe 28. This will swing the bucket 12 to the loading position shown in solid lines 5 in Fig. 5, in which position a charge of carbide will be dumped from the plate 15 into the bucket 12.

The rod 37 is then forced downwardly. It will contact with the upper end of the 10 rod 33 and will force the latter and with it the bell 31 downwardly to the position shown in dotted lines in Fig. 5, in which position the charge of carbide will be dumped from the bucket 12 into the water 15 in the generating chamber 1. The carbide in the water will at once generate gas and will continue such generation for a considerable time after being dumped.

The operation just described is repeated 20 until sufficient pressure is developed, for instance ten pounds, in the generating chamber to open the valve 68 wide enough to supply the gas container 53 with the amount of gas pressure required for use in the torch. 25 This pressure may be regulated by regulating the adjusting screw 74. After such adjustment, the cap 75 is replaced.

The gas which is generated will pass from 30 the generating chamber 1 through the pipe 28, and also through the hopper 4 into the coupling 27, and from thence will pass through the small opening in the ring 29 into the pipe 24, and thence into the bell 31. At each dumping of the bucket 12, more 35 gas is evolved than is required to lift the bell to its uppermost position.

When sufficient pressure accumulates in 40 the bell 31 to lift the bell, the water column around the bell will be lifted and will spread over the top of the bell, and the increasing pressure in the bell, due to the constant generation of the gas from the dumped carbide, will cause the gas in the bell to suddenly 45 burst through the water and to pass above the bell 31 and through the pipe 52 into the container 53.

To lift the bell, the pressure therein must 50 be enough to lift the weight of the bell, the water in chamber 18, the rod 33, and to swing the bucket 12 so as to discharge a charge from the hopper into the bucket 12.

As soon as the gas bursts through the 55 water, the weight of the bell, the water on it, and the rod 33, will cause the bell to instantly drop, as the gas from the charge that has been previously dumped from the bucket into the water can not enter the bell through the restricted opening in the ring 29 fast enough to overcome this weight at 60 the time. The falling bell will swing the bucket 12 so as to dump the last charge therein into the water in the generating chamber 1, thus keeping up the continuous supply of gas flowing through the pipe 28, hopper 4, coupling 27, and pipe 24.

The action just described will remain continuous, as long as the valve 55 is open, and the torch is being used to take gas from the container 53. The valve 55 is opened as soon as the pressure in the generator chamber 1 and container 53 is at the desired working pressure, which, as stated before, is regulated by the adjusting screw 74, which controls the valve 68.

When the pressure of the gas in the chamber 1 opens the valve 68, the gas will pass 75 into the container 53, through the pipe 61, past the check valve 62. The pressure in container 53 will soon be as great as in chamber 1. When the valve 55 is opened and gas 80 is drawn from the container 53 for use in the torch, the pressure in container 53 and chamber 1 will lower, thus permitting the valve 68 to move toward the closed position, thereby restricting the volume of gas flow 85 through the pipe 61 into the container 53. In the meantime, however, gas is constantly being formed in the chamber 1 and is always flowing through the hopper 4 and pipes 28 and 24 into the gas bell 31, and the bell will 90 consecutively be rising and dropping so as to keep up the dumping of carbide into the bucket and from thence into the water.

When the pressure has fallen in the container 53 to a predetermined point, the gas 95 in the pipe 52 will pass the check valve 56 and will enter the container 53, thereby increasing the pressure therein, and in the chamber 1, thus effecting a wider opening 100 of the valve 68, so that more volume of gas 105 will enter the container 53 through the pipe 61.

In this manner a substantially uniform 110 pressure is maintained in the chamber 1 and container 53, as long as a uniform amount of 105 gas is being withdrawn through the open valve 55. The larger amount of gas entering the container 53 will pass through the pipe 61. The function of the gas passing 115 through the pipe 52 is mainly to keep the bell 31 working to supply carbide to the chamber 1 and to retain more uniform the pressure in container 53, the main body of gas used being supplied through the pipe 61 past the valve 68, which is constantly open to a more or less extent, as long as the machine is in operation.

By setting the nut 32 so that small charges of carbide are dumped, the reciprocation of the bell 31 and the dumping of carbide will 120 be softer than when the nut 32 is set to effect the dumping of larger charges, but the pressure maintained in the container 53 and chamber 1 will be more uniform.

As soon as the valve 55 is closed, or the 125 flow through the torch is turned off, the operation of the machine automatically ceases, without any appreciable increase of pressure in the chamber 1 resulting. This is for the reason that in order for the gas bell to op- 130

erate to discharge carbide into the bucket 12 and to dump the charges into the water, the bell must continue to make full strokes upwardly and downwardly, and to lift the bell to effect a discharge of gas therefrom into the pipe 52, there must be less pressure in the latter pipe and above the bell than in the chamber 1, corresponding to the pressure required to lift the bell, the column of water in the chamber 18, the rod 33, and to swing the bucket 12 to discharge the carbide from the plate 15 into the bucket 12.

If gas is not being taken from the container 53, the pressure in the pipe 52 will soon increase to a point at which the pressure from below will be insufficient to lift the bell, the rod 33, and the column of water against the pressure above the bell, and the bell will cease to reciprocate. The last charge 20 or two which has been dumped into the water will be of only sufficient amount to generate but a small quantity of gas, which, due to the large area of the chamber 1, will only effect a very slight increase in pressure in 25 the chamber 1, not enough to lift the bell against the load and pressure from above.

As soon as the valve 55 is opened again, and gas withdrawn therethrough, the pressure will lower in the container 53, and the 30 valve 68 will close slightly, and gas will begin to pass from the pipe 52 into the container 53. When the pressure above the bell 31 lowers to a point that the pressure under the bell will lift the bell to discharge gas 35 therefrom, the operation of the bell will be resumed, as above described.

Assuming that it requires a pressure of two pounds to lift the bell 31, the water in the chamber 18, and to swing the bucket 12 40 to discharge a charge into the bucket, then the pressure in the chamber 1 must be in excess of two pounds greater than the pressure above the bell in order to permit gas to pass from the bell into the pipe 52. Also, 45 the pressure in the container 53 must lower below the pressure in the pipe 52 to permit gas to pass the check valve 56 into the container 53. When this condition occurs, as it does right along, when the valve 55 is 50 open, the valve 68 will move toward the closed position, thus restricting the flow through the pipe 61, and this deficiency will be made up by the gas entering the container 53 through the pipe 52, the evolving of gas 55 in the chamber 1 being continuously effected by the carbide which has already been fed into the water. Thus the pressure in the container 53 will, during the operation of the machine, with the valve 55 open, be 60 slightly below the pressure in the chamber 1, and slightly above and slightly below, consecutively, the pressure in the pipe 52. The variation, however, of pressure in the container 53 will be relatively slight and will 65 not be noticeable in the operation of the

torch. If a larger tip on the torch is used, the bell 31 will operate oftener to supply more carbide to the chamber 1, and if a smaller tip is substituted, the bell will operate less often to reduce the dumping of 70 carbide.

A material increase of pressure in the chamber 1 can not occur, as, when the valve 55 is shut, the pressure accumulating in the container 53 would prevent gas passing from the pipe 52 into the container, and the bell would stop lifting, due to accumulated gas pressure, produced by the last gas burst through the water, above the bell together with the weight of the latter and the water 80 in the chamber 18 to be lifted. The bell would stop the feeding operation, and the small amount of gas generated from the carbide which had already been fed would not produce an appreciable increase in pressure. 85

After the preliminary manual starting of the operation, as described, the angle rod 40, is turned to the vertical position, shown in Fig. 1, in which position, the rod 37 will be held out of the path of the rod 33, so that 90 the operation of the latter would not be interfered with.

The nut 32 is not for the purpose of shutting gas off from the pipe 28, but only for limiting the upward movement of the bell 95 31 to the position in which the desired amount of carbide will be discharged from the plate 15 onto the bucket 12. The gas can always pass into the hopper 4 from the chamber 1, and from the hopper 4 through 100 100 the coupling 27 into the pipe 24.

When it is desired to cease operating the machine, the valve 60 may be closed, thereby stopping the operation of the gas bell and the carbide feeding operation. The same 105 effect is obtained by closing the valve 55.

In starting the machine, it is only needed to manually reciprocate the bell 31 in the manner already described until gas begins to force the water out of the bell and to 110 burst through the water. After this, the machine will operate automatically and the valve 55 may be opened. It is preferable, however, in order to have a full working pressure, as soon as the torch is to be used, 115 to manually operate the bell until the valve 68 opens at the predetermined pressure. As soon as the valve 68 opens, the flow will begin through the pipe 61, and will diminish through the pipe 52, the operation of the bell 31 slowing down as the flow increases 120 through the pipe 61.

I do not limit my invention to the structure shown and described, as many modifications, within the scope of the appended 125 claims, may be made without departing from the spirit of my invention.

What I claim is:—

1. In an acetylene generator, a gas container having an outlet for gas, a gas gener- 130

- ating chamber arranged to contain water, means for feeding carbide into the water, two gas conducting means connected with the generating chamber and discharging into said gas container, means for reducing the flow in one of said conducting means when the pressure in the generating chamber is below a pre-determined amount and which permits the flow when the pressure reaches 10 said amount, the other conducting means being adapted to contain a sealing liquid, a gas bell in said liquid sealing means arranged to receive gas and to be lifted thereby and to discharge the gas so received through said sealing liquid, and means actuated by movement of said gas bell for actuating the carbide feeding means.
2. In an acetylene generator, a gas container having an outlet for gas, a generating chamber arranged to contain water, means for feeding carbide into the water, two gas conducting means connected with the generating chamber and discharging into said gas container, a valve for closing one of said 20 conducting means, means for respectively opening and closing said valve when the pressure in the generating chamber rises to and falls below a pre-determined amount, the other conducting means being adapted to contain a sealing liquid, a gas bell in said liquid sealing means arranged to receive gas passing through said other conducting means from the generating chamber and to be lifted thereby and to discharge the gas so received through said sealing liquid, and means actuated by movement of the gas bell for actuating the carbide feeding means.
3. In an acetylene generator, a gas container having an outlet for gas, a gas generating chamber arranged to contain water, means for feeding carbide into the water, gas conducting means connected with the generating chamber and discharging into said container and including a closed receptacle adapted to contain a sealing liquid and provided with a gas outlet above said sealing liquid and having a gas inlet, a gas bell in said sealing liquid into which the said inlet discharges, the gas bell being arranged to be 40 lifted by the gas received and to discharge the gas through said liquid, and means actuated by movement of said gas bell for actuating said carbide feeding means.
4. In an acetylene generator, a gas generating chamber arranged to contain water, means for feeding carbide into the water, a closed receptacle adapted to contain a sealing liquid and having an outlet above said liquid, a gas conductor connected to said generating chamber and discharging into said receptacle, a gas bell in said sealing liquid into which said conductor discharges arranged to be lifted by the gas it receives and to discharge said gas around its lower end through said liquid, a gas container, a conductor connecting said outlet and said container, and a member connected to and movable with said gas bell extending through said first named conductor and connected with and adapted to actuate said feeding means.
5. In an acetylene generator, a gas generating chamber arranged to contain water, means for feeding carbide into the water, a closed receptacle adapted to contain a sealing liquid and having an outlet above said liquid, a gas conductor connected with said generating chamber, a gas bell in said liquid into which said conductor discharges arranged to be lifted by the gas it receives and to discharge the gas around its lower end through said liquid, manually operated means for vertically moving said gas bell, a gas container, a conductor connecting said outlet and said container, and means actuated by movement of the gas bell for operating said carbide feeding means.
6. In an acetylene generator, a gas generating chamber arranged to contain water, means for feeding carbide into the water, a closed receptacle adapted to contain a sealing liquid and having a gas outlet above said liquid, a gas conductor connected with said generating chamber, a gas bell in said liquid into which the gas conductor discharges arranged to be lifted by the gas it receives and to discharge the gas around its lower end through the liquid, adjustable means for limiting the upward movement of the gas bell, a gas container, a conductor connecting said outlet and said container, and means actuated by movement of the gas bell for operating said carbide feeding means.
7. In an acetylene generator, a gas generating chamber arranged to contain water, means for feeding carbide into the water, a closed receptacle adapted to contain a sealing liquid, and having a gas outlet above said liquid, a gas conductor connected with the generating chamber, a gas bell in said liquid arranged to receive gas from said conductor and to be lifted by the gas and to discharge the gas around its lower end through said conductor and connected to and operated by movement of the gas bell for actuating said carbide feeding means, a gas container, a conductor connecting said outlet and said container, and manually operated means for vertically moving said gas bell.
8. In an acetylene generator, a gas generating chamber arranged to hold water, means for feeding carbide into the water, a closed receptacle adapted to contain a sealing liquid and having an outlet above the liquid, a gas conductor connected with the generating chamber, a gas bell in said liquid into which the conductor discharges arranged to be lifted by the gas and to discharge the gas around its lower end through said liquid, a gas container, a conductor connecting said outlet and said container, and manually operated means for vertically moving said gas bell.

the liquid, means actuated by movement of the gas bell for operating the carbide feeding means, a gas container arranged to hold a liquid, and a conductor connected with said outlet and discharging into the gas container below the level of the liquid in the container.

9. In an acetylene generator, a gas generating chamber arranged to hold water, means for feeding carbide into the water, a closed receptacle adapted to contain a sealing liquid and having a gas outlet above said liquid, a gas conductor connected with the generating chamber, a gas bell in said liquid into which the conductor discharges arranged to be lifted by the gas it receives and to discharge the gas around its lower end through the liquid, means actuated by movement of the gas bell for operating the carbide feeding means, a gas container adapted to contain liquid, a conductor connected with said outlet and discharging into the gas container below the level of the liquid therein, and manually operated means for vertically moving said gas bell.

10. In an acetylene generator, a gas generating chamber arranged to hold water, means for feeding carbide into the water, a closed receptacle adapted to contain a sealing liquid and having a gas outlet above the liquid, a gas conductor connected with the generating chamber, a gas bell in said liquid into which the conductor discharges arranged to be lifted by the gas it receives and to discharge the gas around its lower end through the liquid, an operating member extending through said conductor and connected with and movable by movement of the gas bell and arranged to operate the feeding means, a gas container, a conductor connecting said outlet and said container, and a manually operated member recipro-
cative in said receptacle and arranged to engage and vertically move said gas bell.

11. In an acetylene generator, a gas generating chamber arranged to hold water, means for feeding carbide into the water, a closed receptacle adapted to contain a sealing liquid and having a gas outlet above the liquid, a gas conductor connected with the generating chamber, a gas bell in said liquid into which the conductor discharges arranged to be lifted by the gas it receives and to discharge the gas around its lower end through the liquid, an operating member connecting the gas bell and the feeding means, a gas container, a conductor connecting said outlet and said container, and a manually operated member recipro-
cative in said receptacle and having means for engaging and vertically moving said gas bell.

In testimony whereof I have signed my name to this specification.

ISAAC M. HACKNEY.
